UNITED STATES PATENT OFFICE.

AMOS B. TAYLOR AND JACOB P. TIRRELL, OF BOSTON, ASSIGNEES TO
WILLIAM S. LAMSON, OF LOWELL, MASSACHUSETTS.

BUFFER AND CATCH FOR CASH-CARS.

SPECIFICATION forming part of Letters Patent No. 393,039, dated November 20, 1888.

Application filed December 4, 1885. Serial No. 184,735. (No model.)

To all whom it may concern:

Be it known that we, AMOS B. TAYLOR and JACOB P. TIRRELL, citizens of the United States, and residents of Boston, Suffolk county, 5 Massachusetts, have invented certain new and useful Improvements in Buffers and Catches for Cash-Cars, of which the following is a specification.

Our invention relates to that class of store- 10 service apparatus in which a car moves back and forth on a way and is arrested by stops at each terminus; and our invention consists in constructing the stop and disconnecting devices, and in providing the car with yielding 15 buffers or contact-pieces, as fully set forth hereinafter, so as to gradually arrest the car without shocks or jolts and release the same by the motion of the hand, which starts the car on its return movement.

20 In the drawings, Figure 1 is a side elevation showing a track, stop, and sufficient of a car to illustrate our improvements. Fig. 2 is a plan of Fig. 1. Fig. 3 is a section on the line 1 2, Fig. 1, looking in the direction 25 of the arrow U. Fig. 4 is a transverse view illustrating a modification. Fig. 5 is a side elevation showing a modification. Fig. 6 is a detached enlarged section of a modified friction device. Fig. 7 is a side elevation in part 30 section showing another modification.

The frame A of the car is constructed in any suitable manner according to the style of the car and is provided with wheels Q, adapted to the track upon which the car is to run—as, 35 for instance, a wire track, B. To the track, near each end thereof, is secured a stop device, C, which may be of any suitable construction. As shown, it consists of a tapering cylinder or cone, a, mounted upon the wire, a cylindrical block of rubber, b, fitting in the end of the cone a axially therewith, and a clamp 40 consisting of two pieces, c d, the former secured to the cone a, and the latter clamped to the piece c and to the intervening wire B by means of screws e, thus holding the stop device firmly in any position to which it may 45 be set upon the wire.

To the stop device is connected a yielding catch, D, which has a shoulder, x, and in- 50 clined end, the yielding quality of the catch

resulting either from the use of a spring-shank, as in the construction shown in full lines, or from pivoting it at one end to the stop, as shown in dotted lines, Fig. 1, the attachment in any case being such that some part of the 55 car or device carried thereby will move the catch by contact with the beveled face thereof until such part passes the shoulder x, which will then engage with said part as the catch is thrown inward, thereby holding the car. 60

In the construction shown in the drawings the part that connects with the catch is an arm, E, which is pivoted at the lower end to an arm, F, projecting from the car, the arm E terminating in a disk or plate, f, having a 65 central opening, y, for the passage of the track-wire B, as the arm is carried with the car and the edge of the disk being beveled where it makes contact with the inclined face of the catch, so as to facilitate the throwing outward 70 of the latter as the disk passes the catch.

In order to release the car from the stop, we make use of a movable arm, lever, wedge, or other device, which by its movement is brought in contact with the catch and throws outward 75 the end thereof until the shoulder x is carried from its position opposite the disk, when the car can be readily returned along the track to the position from which it started.

Different appliances will occur to those 80 skilled in the art for throwing outward the catch. In Figs. 1 to 3 we have shown an L-shaped lever, G, pivoted to the arm E, and to one arm of the lever is connected a cord, g, which extends downward through an eye, h, 85 upon the arm and carries a pull, j, whereby the cord may be drawn down to turn the lever in the direction of the arrow, Fig. 3, and thereby bring the vertical arm of the lever against the catch and throw the latter outward to the position shown in dotted lines, thus releasing it 90 from its engagement with the car. 90

Inasmuch as the lever G and its operating appliances are carried by the car, the latter may be propelled upon its return movement 95 by the same movement that is employed to disconnect it from the stop. For instance, by pulling upon the cord g in the direction of the arrow X, Fig. 1, the lever G is first thrown outward and disconnects the stop from the car, 100

and the continued pull in the same direction projects the car along the way in the direction of the arrow Y, Fig. 1.

In Fig. 4 we have illustrated another form 5 of disconnecting device, the same being a wedge or triangular plate, G², sliding vertically upon the arm E and acting at its opposite edges upon the heads of two catches, D D, upon opposite sides of the way, so as to throw both of 10 them out when the disconnecting device is drawn downward. In this case the plate G² is connected to a stiff operating-rod, g', formed in one piece with a handle or pull, j, and sliding in eyes or guides m m upon the arm E, and 15 a spring, n, bearing upon a shoulder, n', of the rod g', lifts the latter and the plate, when pressure is removed from the handle.

It will be evident that when the catch is differently constructed from that shown the 20 detaching device must be correspondingly varied.

It has been common to reduce the impact of 25 the car by the use of spring stops or buffers mounted upon the way, the springs being compressed by the contact of the car with some portion of the buffer. In other instances spring- 30 buffers have been arranged upon the cars. We have found that it is advantageous to use a friction device or brake to resist the momentum, thereby avoiding the necessity of always employing springs, and also securing a 35 more uniform resistance during the movement of the car in contact with the stop. Different modes of carrying out this means of frictional resistance will occur to those skilled in the art, and we will now describe two arrangements which may be employed for the purpose of 40 illustrating our invention.

In Figs. 1 to 3 the arm E is shown as enlarged to form a disk, p, coinciding with a similar disk, p', upon the arm F, and a bolt, q, extends centrally through both disks, and is provided with a nut, r, whereby the disks may be brought together upon an intervening 45 sheet or disk, s, of leather, felt, or other suitable material. By turning the nut r the pressure of the disks upon the intervening material may be varied as required, and according as the pressure increases an increased resistance to the movement of the arm E upon its 50 pivot will be secured. As the car is brought to the stop, the end of the arm E strikes the same and the arm is turned upon its pivot with a frictional resistance, which finally results in absorbing the momentum and arresting the car. A spring, J, may be used to supplement the frictional resistance, and also, as in the arrangement shown in Figs. 1 to 3, to 55 throw outward the arm E after it has moved inward under the impact with the stop; but the necessity of using a spring for the latter purpose may be avoided by connecting two pivoted arms, E E', together by a connecting-rod, I, as shown in Fig. 5, so that when one 60 arm is moved in it will cause the other to be thrown out. In such case the frictional re-

sistance can be applied to the connecting-rod I in any suitable manner—for instance, by means of a packing, s, confined in a packing-box, K, and compressed by means of a follower, L, the rod I sliding through the box, as shown in Fig. 6.

In Fig. 7 the arms E² E³, instead of being pivoted, as are the like arms E E', before described, are connected to the ends of two sliding rods, N N, sliding in bearings upon the frame, so that when one arm is moved in the other will be moved out, and springs J J may constitute the resistance or may supplement the action of friction devices—as, for instance, packings in boxes K K—through which one of the rods N slides.

It will be evident that the catch, instead of being secured to the fixed stop upon the wire, may be secured to the wire itself, the stop being an independent device, and that the stop while shown and claimed as mounted upon the way may be mounted adjacent thereto without departing from the gist of our invention.

Without limiting ourselves to the precise 90 construction and arrangement of parts shown, we claim—

1. The combination of the way, fixed stop secured to the way, catch carried by the stop, and a yielding buffer carried by the car and 95 arranged to engage with the catch, and a detaching device carried by the car independently of the catch, substantially as set forth.

2. The combination of a fixed stop secured to the way, a yielding buffer carried by the 100 car and arranged to make contact with the said stop, a catch combined with the stop and arranged to engage with the said buffer before the latter makes contact with the stop, and a detaching device carried by the car independently 105 of the catch and constructed to disconnect the catch from the car, substantially as set forth.

3. The combination, with the stop and catch, of a car having a yielding buffer which is arranged to engage with the stop, and a catch-detaching device carried by the car independently 110 of the catch, provided with a pendent handle or pull, substantially as set forth.

4. The combination of the fixed stop and 115 catch with the car carrying a yielding buffer concentric with the way and arranged to make contact with the stop and catch, and a catch-detaching device provided with a pendent handle or pull, substantially as described. 120

5. The combination, with a car and a way having a stop and catch, of a yielding buffer on the car arranged to contact with the catch, and a detaching device independent of the catch arranged to remove the latter from contact with the buffer, substantially as set forth. 125

6. The combination of a car and a buffer at each end thereof connected movably to said car and adapted to engage with a catch upon the way, a lever pivoted to said buffer and arranged to bear against the catch and release the buffer therefrom, and a pendent handle or 130

pull connected to said lever, substantially as set forth.

7. A car provided at each end with a pivoted buffer-arm carrying a catch-detaching device, and a spring arranged to throw the arm outward, substantially as described.

8. A car provided with a buffer arranged to make contact with a stop upon the track, and a friction-brake arranged to resist the movement of the arm, substantially as described.

9. The combination of the car, a buffer, a friction-brake, and a spring arranged to throw the arm of the buffer outward, substantially as described.

10. The combination of the car, a buffer-arm carried thereby and arranged to make contact with a stop upon the way, said buffer-arm being pivoted to the car-frame, and a friction-brake interposed between the arm and frame, substantially as described.

11. The combination, with the car and connected buffer-arms at opposite ends thereof, of a friction-brake interposed between the arms to resist the movements thereof, substantially as set forth.

12. The combination, with the way, a fixed stop secured to the way, and a laterally-yielding catch carried by the stop, of a buffer carried by the car, adapted to engage with the catch, and a catch-detaching device to detach the catch from the buffer, substantially as described.

In testimony whereof we have signed our names to this specification in the presence of two subscribing witnesses.
